TEMPERATURE CONTROL MEANS

Arthur J. Whitcomb, Chicago, Ill., assignor to
 Freyn Engineering Company, Chicago, Ill., a
 corporation of Maine

Application January 24, 1941, Serial No. 375,763

7 Claims. (Cl. 238—15)

The present invention relates to improvements in temperature control means.

The present invention is applicable to and will be described in connection with means for controlling the temperature within the dome of a blast furnace stove, though as the description proceeds it will be apparent that the invention has a broader application.

The modern blast furnace gas stove burner affords such close control of excess air that the products of combustion may be limited to as little as 0.5 per cent of oxygen. Combustion temperatures may range from 2000 to 2400 deg. F. when burning blast furnace gas which ranges from 88 to 96 B. t. u. per cubic foot. In view of the high rate of combustion required to maintain line heats in the neighborhood of 1400 to 1500 deg. F., there is danger of exceeding the safe working temperature of the combustion chamber, the top checkerbrick and the dome lining. If excessive temperatures are maintained, glazing and dropping of the brick may result. Even deformation of the top layers of the checkers may occur due to such high temperatures. It has been common practice to equip the domes of blast furnaces with thermocouples and pyrometers, the readings serving as guides to the stove tenders for the manual operation of the burners.

United States Letters Patent No. 1,817,219, granted August 4, 1931, in the name of Frederick H. Willcox and John C. Hayes, Jr., discloses and claims apparatus for controlling the delivery of combustion air to a blast furnace stove, said apparatus including means for varying the quantity of air delivered proportionally to the presence of the blast furnace gas delivered to the stove burner. The present invention contemplates a control embodying certain of the principles of said Letters Patent No. 1,817,219, it being preferred to utilize an adjustable speed direct current motor for operating the blower to supply the combustion air, speed adjustment during at least a part of the speed range being obtained by adjustment of the field strength of the motor.

A blast furnace stove is a heat storage medium which is heated over a period by delivery of fuel in more or less uncontrolled quantity. In the first part of a heating cycle, when the refractory heat absorbing media are at low temperature, it is possible and desirable to supply a quantity of combustion air which will give efficient combustion and which will also give the highest possible flame temperature in view of the fact that

5 a lean fuel is used—namely, blast furnace gas, and as high a flame temperature as can be obtained by burning cold blast furnace gas with cold air is desirable. This high flame temperature is advantageous in that it increases the temperature difference between the flame and the refractories, thereby increasing the rate of heat transfer to the latter.

10 As the heating cycle progresses, the temperature of the refractories increases. A point is finally reached when the refractories in the combustion chamber attain as high a temperature as is safe for them. However, the refractories in the checker portion of the stove have not yet 15 been raised sufficiently in temperature. Therefore, further operation of the stove on gas is required.

15 It would perhaps be possible to continue operations safely by decreasing the rate of fuel input, thereby restricting the temperature attained by the refractories in the combustion chamber of the stove. However, this would not be desirable as the restricted heat input would mean a greatly 20 delayed rate of heating the checker brick in the stove and would not utilize all available fuel.

25 It is preferable to continue the original rate of heat input, i. e., fuel input, but to prevent the refractories in the combustion chamber from attaining an excessive temperature by the expedient of increasing the input of combustion air whereby to restrict the flame temperature to a sufficiently low value so that there is substantially no temperature difference between the flame and the refractories in the combustion 30 chamber. In this manner the heating of the checkers of the stove can be continued at the original rate of heat input without jeopardizing the refractories in the combustion chamber and the dome of the stove.

35 40 It is well known to blast furnace operators that in heating up a blast furnace stove the rate of heat absorption when the stove is relatively cold is so high that the flame temperature is decidedly limited. In other words, though the blast furnace gas being delivered to the stove has a possibility of a flame temperature in the neighborhood of 2300° or 2400° F., the relatively cool refractories within the stove absorb 45 heat so rapidly that flame temperature may not reach more than 1800° to 1900° F. Under these conditions it has been common practice to supply all of the gaseous fuel available and to supply an amount of combustion air to produce the 50 most efficient burning to achieve a flame tem-

perature as high as possible. This ratio of combustion air to gaseous fuel, according to well known practice, has been maintained until the vulnerable parts of the stove have reached their highest safe temperature. Using specific figures by way of example, the highest safe temperature of the stove may be in the neighborhood of 2100°, whereas the possible flame temperature of the gaseous fuel may be in the neighborhood of 2400° F. It has long been realized that the continuing supply of flame at excess temperature in proximity to the parts of the stove which have already acquired their maximum safe temperature of 2100° endangers the stove. However, as has been well understood, the checkers within the stove may be far below their desired temperature when this dangerous condition in a more vulnerable part of the stove, such as the dome, has been reached.

It is desirable that a flame temperature be maintained as high as possible to heat these checkers without overheating the vulnerable parts of the stove which have already reached their maximum temperature of 2100° F. Accordingly it is desirable to continue the supplying of gas with an amount of combustion air mixed therewith to provide this temperature in the neighborhood of 2100°.

It may be stated, therefore, that the heating cycle of a blast furnace stove is divided into two stages: (a) before the vulnerable parts of the stove have achieved their critical temperature, in which case the most efficient ratio between gas and air should be maintained, and (b) after the vulnerable parts of the stove have achieved their critical temperature, during which stage the full amount of available gas should be delivered with an excess supply of air to hold the flame temperature to the critical value of the neighborhood of this critical temperature.

An object of the present invention is to provide means for protecting a stove or the like from excess temperatures, which means includes means for automatically directing surplus air to the burner of said stove when the temperature in said stove tends to rise above a predetermined value.

A further object is to provide a control means for a burner which will automatically vary the ratio of air and gas to lower the combustion temperature when said temperature tends to rise above a predetermined value.

A further object is to provide control means for a burner which automatically maintains a predetermined mixture of air and gas regardless of variations in gas pressure, which control means includes means for modifying said mixture if and when predetermined temperatures are attained.

A further object is to provide a stove burner control mechanism well adapted to meet the needs of commercial operation.

Further objects will appear as the description proceeds.

The one figure of the drawing illustrates diagrammatically one embodiment of the present invention applied to a blast furnace stove.

A blast furnace stove is indicated by the numeral 10. The numeral 11 indicates a thermocouple, or other temperature responsive device, which is electrically connected to a meter 12, which may be of the well known indicating and recording type. Such meters are commercial equipment and need not be described in detail. The movable pointer 13 of said meter is adapted at two regions of its range of movement to se-

lectively bridge the pair of contacts 14 or the pair of contacts 15.

The numeral 16 indicates a relay provided with the switch 16-S, the closing coil 16-C and the opening coil 16-O for operating said switch. Adjacent terminals of the coils 16-C and 16-O are connected to the electric conductor 17. One of the contacts 14 and one of the contacts 15 are jointly connected to the electrical conductor 18, said conductors 17 and 18 forming the two sides of an electric circuit. It will be clear that when the pointer 13 is in bridging relationship with the contacts 14-14 the coil 16-C will be connected in circuit across the electrical conductors 17 and 18. When said pointer 13 is in bridging relationship with the contacts 15-15 the opening coil 16-O is connected in circuit across the electrical conductors 17 and 18. Said coils 16-C and 16-O have the function, respectively, of closing or opening the switch 16-S forming part of the relay 16. The relay 16 is of the type wherein the switch 16-S, after being closed by energization of the coil 16-C, will remain closed until the opening coil 16-O is energized. Such relays are available commercially and need not be described in detail.

The numeral 19 indicates a relay having the operating winding 19-W and the switch 19-S. Said switch 19-S is adapted in its biased position to short-circuit the resistor 20.

When the switch 16-S of the relay 16 is closed, the winding 19-W of the relay 19 is connected in circuit across the electrical conductors 17-18 and will move the switch 19-S out of its biased position, thereby removing the short-circuit from across the resistor 20.

The numeral 21 indicates a burner for directing gas and air to the stove 10. The numeral 22 indicates a conduit for delivering gas to said burner 21, and the numeral 23 indicates a motor driven blower for directing air to said burner 21. The motor of said blower 23 is provided with the field winding 24, one terminal of which is connected to the electrical conductor 17 and the other terminal of which is connected to the governing means 25. Said governing means 25 includes the variable resistor 26, the effective resistance of which is controlled by means of the movable contact 27. Accordingly the blower 23 will be controlled to maintain one definite ratio of air to gas supply when the meter 12 indicates a predetermined maximum temperature and another definite ratio of air to gas supply when said meter indicates a predetermined lower temperature. Said governing means 25 may be connected up to be responsive to the pressure of gas admitted to the burner 21, according to the principles set forth in Letters Patent No. 1,817,219 above referred to. Certain mechanism for accomplishing this purpose is illustrated in the drawing, in which conduit 28 leads from the conduit 22 to the diaphragm housing 29. The diaphragm (not shown) in said housing is connected to the rod 30, which through the link 31 controls the lever 32 to swing about the pivot 33. Said lever 32 carries the contact 27 at one end thereof. The other end of said lever 32 operates against an extremity of the compression spring 34.

The mode of operation of the above described embodiment of the present invention is substantially as follows: The thermocouple or pyrometer 11 is actuated in response to temperature changes in the dome of the stove 10 to control the position of the pointer 13 of the meter 12.

When the meter 12 indicates a maximum safe temperature, the pointer 13 bridges the contacts 14-14, energizing the coil 16-C to close the switch 16-S. Closure of the switch 16-S results in the energization of the winding 19-W, opening the short-circuit around the resistor 20. By reason of the insertion of the resistor 20 in circuit, the speed of the motor driven blower 23 is increased, so that, considering any given gas pressure, there is an increase in the quantity of air delivered to the stove 10. In this manner an excess amount of air is supplied to restrict the temperature in the dome of the stove.

As the dome temperature diminishes, the pointer 13 moves away from the contacts 14-14, but, as explained above, the switch 16-S of the relay 16 is maintained closed, holding the switch 19-S in its unbiased position. As the dome temperature continues to decrease, the pointer 13 will move into bridging relationship with the contacts 15, thereby energizing the opening coil 16-O of the relay 16 and opening the switch 16-S thereof, allowing the switch 19-S to again move into short-circuiting relationship with the resistor 20, causing the slowing down of the motor driven blower 23.

Under these conditions the field winding 24 is responsive directly to the governing means 25, which operates, as above explained, to vary the pressure delivered by the blower 23 in accordance with variations in pressure in the gas supply conduit 22, as fully explained in Letters Patent No. 1,817,219 above referred to.

The present invention has the advantage that relatively fast rates of combustion may be safely utilized and relatively high quantities of heat can be stored in the stove without the need for close watchfulness on the part of the stove tender and without danger of overheating the dome. Due to the sensitivity of the equipment the temperature of the stove dome can be maintained within close limits. As the control responds directly to the dome temperature, any variation in gas quality affects only the proportion of time that the abnormal ratio control between air and gas is being had. The degree of ratio distortion, that is, the amount of excess air admitted, can be set so as to reduce the temperature of the stove dome without excessive loss of efficiency. In practice there is sufficient lag in the system to prevent any fluttering of the control.

Though a preferred embodiment of the present invention has been described in detail, many modifications will occur to those skilled in the art. It is intended to cover all such modifications that fall within the scope of the appended claims.

What is claimed is:

1. In combination, a burner, means for supplying gas to said burner, means for supplying combustion air to said burner, said air supplying means being adapted to supply a substantial excess of air above that required for efficient combustion of any normal gas quantity supplied to said burner, means for providing two predetermined ratios between the amount of air and the amount of gas supplied to said burner by said supplying means independently of any control of the supply of said gas, the lower of said ratios having just sufficient air to provide efficient combustion, the higher of said ratios providing an excess of air which is high enough to substantially reduce the combustion temperature, temperature responsive means, and means controlled by said temperature responsive means.

5 for selecting the higher ratio of air to gas upon attainment of a predetermined high temperature and for restoring the lower ratio of air to gas upon the attainment of a predetermined lower temperature.

2. In combination, a burner, means for supplying gas to said burner, means for supplying air to said burner, said air supplying means being adapted to supply a substantial excess of air above that required for efficient combustion of any normal gas quantity supplied to said burner, means for providing two predetermined ratios between the amount of air and the amount of gas supplied to said burner by said supplying means independently of any control of the supply of said gas, the lower of said ratios having just sufficient air to provide efficient combustion, the higher of said ratios providing an excess of air which is high enough to substantially reduce the combustion temperature, temperature responsive means, and a relay controlled by said temperature responsive means, said relay being adapted to select the higher ratio of air to gas upon attainment of a certain predetermined position by said temperature responsive means and to hold said higher predetermined ratio of air to gas until said temperature responsive means attains a predetermined different position responsive to a predetermined lower temperature.

3. In a blast furnace stove installation, in combination, a blast furnace stove having a temperature responsive member in the portion thereof most vulnerable to excessive heat conditions, means for delivering combustion air to said stove, means for delivering combustible gas to said stove, said air delivering means being adapted to supply a substantial excess of air above that required for efficient combustion of any normal gas quantity supplied to said stove, means for providing two predetermined ratios between the supply of said air and the supply of said gas delivered to said stove independently of any control of the supply of said gas, the lower of said ratios having just sufficient air to provide efficient combustion, the higher of said ratios providing an excess of air which is high enough to substantially reduce the combustion temperature, and means responsive to said temperature responsive member for selecting the higher ratio of said air to said gas when said temperature responsive member indicates a predetermined high temperature and for restoring the lower of said ratios when said temperature responsive member indicates a lower temperature.

4. In heat transfer mechanism, subject to alternate stages of receiving heat and giving off heat, in combination, a heat transfer member having a temperature responsive member in the portion thereof vulnerable to excessive heat conditions, said heat transfer member being provided with a burner, means for supplying gas to said burner, means for supplying combustion air to said burner, said air supplying means being adapted to supply a substantial excess of air above that required for efficient combustion to any normal gas quantity supplied to said burner, means for providing two predetermined ratios between the amount of air and the amount of gas delivered to said burner independently of any control of gas delivered to said burner, the lower of said ratios having just sufficient air to provide efficient combustion, the higher of said ratios providing an excess of air which is high enough to substantially reduce the combustion temperature, and means responsive to said tem-

perature responsive member for selecting the higher ratio of air to gas when said temperature responsive member indicates a predetermined high temperature and for selecting the lower ratio of air to gas when said temperature responsive member indicates a lower temperature.

5. In a blast furnace stove installation, in combination, a blast furnace stove having the usual heat transfer media and a portion vulnerable to excessive flame temperatures, a burner for said stove, means for delivering gas to said burner, means for delivering air to said burner, said air delivering means being adapted to supply a substantial excess of air above that required for efficient combustion of any normal gas quantity supplied to said burner, means for maintaining two predetermined ratios between the amount of air and the amount of gas supplied to said burner independently of any control of the supply of said gas, the lower of said ratios having just sufficient air to provide efficient combustion, the higher of said ratios providing an excess of air which is high enough to substantially reduce the combustion temperature, and means responsive to temperature at said vulnerable portion operative when the temperature at said vulnerable portion reaches a predetermined value to select the higher ratio of air to gas, whereby during the first stage of the cycle of heating said stove the ratio of air to gas is maintained for the production of maximum combustion temperature and after said vulnerable portion has acquired a predetermined critical temperature the ratio of air to gas is increased to limit said combustion temperature to a value safe with respect to said critical temperature of said vulnerable portion.

6. In combination, a burner, means for supplying gas to said burner, means for supplying combustion air to said burner, said air supplying means being adapted to supply a substantial excess of air above that required for efficient combustion of any normal gas quantity supplied to said burner, governing means for providing two

predetermined ratios between the amount of air and the amount of gas supplied to said burner by said supplying means independently of any control of the supply of said gas, the lower of said ratios having just sufficient air to provide efficient combustion, the higher of said ratios providing an excess of air which is high enough to substantially reduce the combustion temperature, temperature responsive means, and means controlled by said temperature responsive means for selecting the higher ratio of air to gas supply for increasing the delivery of air upon the attainment of a predetermined high temperature as indicated by said temperature responsive means.

7. In heat transfer mechanism, subject to alternate stages of receiving heat and giving off heat, in combination, a heat transfer member having a temperature responsive member in the portion thereof vulnerable to excessive heat conditions, said heat transfer member being provided with a burner, means for supplying gas to said burner, means for supplying combustion air to said burner, said air supplying means being adapted to supply a substantial excess of air above that required for sufficient combustion of any normal quantity supplied to said burner, means for providing two predetermined ratios between the amount of air and the amount of gas supplied to said burner independently of any control of the amount of gas delivered to said burner, the lower of said ratios having just sufficient air to provide efficient combustion, the higher of said ratios providing an excess of air which is high enough to substantially reduce the combustion temperature, and means responsive to said temperature responsive means for selecting the higher ratio of air to gas when said temperature responsive member indicates a predetermined high temperature and for selecting the lower predetermined ratio of air to gas when said temperature responsive member indicates a lower temperature.

perature responsive member for selecting the higher ratio of air to gas when said temperature responsive member indicates a predetermined high temperature and for selecting the lower ratio of air to gas when said temperature responsive member indicates a lower temperature.

5. In a blast furnace stove installation, in combination, a blast furnace stove having the usual heat transfer media and a portion vulnerable to excessive flame temperatures, a burner for said stove, means for delivering gas to said burner, means for delivering air to said burner, said air delivering means being adapted to supply a substantial excess of air above that required for efficient combustion of any normal gas quantity supplied to said burner, means for maintaining two predetermined ratios between the amount of air and the amount of gas supplied to said burner independently of any control of the supply of said gas, the lower of said ratios having just sufficient air to provide efficient combustion, the higher of said ratios providing an excess of air which is high enough to substantially reduce the combustion temperature, and means responsive to temperature at said vulnerable portion operative when the temperature at said vulnerable portion reaches a predetermined value to select the higher ratio of air to gas, whereby during the first stage of the cycle of heating said stove the ratio of air to gas is maintained for the production of maximum combustion temperature and after said vulnerable portion has acquired a predetermined critical temperature the ratio of air to gas is increased to limit said combustion temperature to a value safe with respect to said critical temperature of said vulnerable portion.

6. In combination, a burner, means for supplying gas to said burner, means for supplying combustion air to said burner, said air supplying means being adapted to supply a substantial excess of air above that required for efficient combustion of any normal gas quantity supplied to said burner, governing means for providing two

predetermined ratios between the amount of air and the amount of gas supplied to said burner by said supplying means independently of any control of the supply of said gas, the lower of said ratios having just sufficient air to provide efficient combustion, the higher of said ratios providing an excess of air which is high enough to substantially reduce the combustion temperature, temperature responsive means, and means controlled by said temperature responsive means for selecting the higher ratio of air to gas supply for increasing the delivery of air upon the attainment of a predetermined high temperature as indicated by said temperature responsive means.

7. In heat transfer mechanism, subject to alternate stages of receiving heat and giving off heat, in combination, a heat transfer member having a temperature responsive member in the portion thereof vulnerable to excessive heat conditions, said heat transfer member being provided with a burner, means for supplying gas to said burner, means for supplying combustion air to said burner, said air supplying means being adapted to supply a substantial excess of air above that required for sufficient combustion of any normal quantity supplied to said burner, means for providing two predetermined ratios between the amount of air and the amount of gas supplied to said burner independently of any control of the amount of gas delivered to said burner, the lower of said ratios having just sufficient air to provide efficient combustion, the higher of said ratios providing an excess of air which is high enough to substantially reduce the combustion temperature, and means responsive to said temperature responsive means for selecting the higher ratio of air to gas when said temperature responsive member indicates a predetermined high temperature and for selecting the lower predetermined ratio of air to gas when said temperature responsive member indicates a lower temperature.
